TEMPERATURE CONTROL INSTRUMENTS

Charles H. Strange, Jacksonville Beach, Fla., assignor to
Elsa L. Strange, Jacksonville Beach, Fla.

Application January 28, 1954, Serial No. 406,842

9 Claims. (Cl. 200—137)

This invention relates to temperature responsive or control instruments for use up to about 2400° F. and more particularly to improvements in such devices as described in my co-pending application Serial Number 330,195, filed January 8, 1953, and Serial Number 389,278, filed October 30, 1953.

In the latter application I disclosed a thermocouple of two alloys or metals "Inconel" and "Kanthall" and the compositions of each metal.

It is an object of this invention to provide an instrument of the type described in said application, Serial Number 389,278 in which one thermostat expansion element also functions as an element of a thermocouple. Such a combination affords many outstanding advantages not only because the above mentioned thermocouple metals produce a thermal E. M. F. almost exactly equal to that of the much more expensive platinum-rhodium couple, but because the readings of the E. M. F. indicate the conditions of the thermostat elements.

The inventive features for attaining these and many more objects are shown herein in connection with a temperature responsive instrument which briefly described includes an element serving as a thermocouple element and an expansion element at the same time and formed from a cheap known metal.

In the accompanying drawing showing, by way of example, one of many possible embodiments of the invention:

The drawing shows a longitudinal cross section of the instrument.

"Inconel" is a known alloy melting at about temperatures of the order of 2500° F. and composed of approximately 79.5% Ni; 13% Cr; 6.5% Fe; 0.25% Mn; 0.25% Si; 0.20% Cu; and 0.08% C and having a coefficient of expansion of about 0.64×10^{-5} .

"Kanthall" is likewise a known alloy melting at temperatures of the order of 2750° F. and is composed of approximately 0.25 max. C; 0.3-2.0% Si; 18-25% Cr; 3.5-6.5% Al; nil-3.0% Co; nil-3.0% Ta; 0.2-1.0% Mn and the balance Fe, and having a coefficient of expansion of the same order as that of "Inconel."

Hereinafter "Inconel" is sometimes referred to as "alloy A" and "Kanthall" as "alloy B."

The device comprises a tube or expansion element 10 of Inconel closed at the inner end 11 except for a small hole 12 therein and adapted to be disposed through a hole 14 in a kiln wall 15. Within the end portion 16 of the tube 10, which project into the kiln, there is disposed a porcelain tube 18 which does not soften below about 3000° F. While porcelain is the preferred material, other materials having high melting or softening points of the order of 3000° F. and above, negligible thermal expansion, and high electrical insulating properties may be used.

The inner end 19 of the porcelain tube abuts against the end 11 of the outer metal tube 10 while the outer end 20 of porcelain tube is free to move relative to the outer tube 10 due to expansion and contraction of the tube portion 16 during temperature changes. The porcelain tube undergoes virtually no expansion and contraction over a wide range of temperature, and there is relative movement between the end 20 and the adjacent portion of the tube 10 due to the great difference in expansion of porcelain and metal.

Relative movement of the tube end 20 and the tube 10 thereat, is transmitted beyond the outer end 21

of the tube 10 by a transmission rod or member 22 of Kanthal having an end 24 easily fitting within the bore 25 of the porcelain tube and shoulder 26 against the end 20 and out of contact with the metal tube 10.

The transmission rod 22 extends coaxially with the tube 10 beyond the end 21 thereof and is disposed through a slide bearing 28 of hard electrical insulating material such as asbestos board secured on the end 21 of tube as by a screw 29. The opening 30 of the bearing may be bushed as at 31 with metal to afford easy movement if desired, but the rod must not come in electrical contact with the end of the tube 10. A spring 32 compressed between a shoulder 34 on the rod inner of the bearing and the bearing urges the rod and porcelain tube inwardly so that there is never any lost motion between the two.

The portion 35 of the rod passing out through the bearing is employed to actuate a control button 36 of a microswitch 38. The switch is mounted by means of a pivot member 39 in and on a housing 40 into which the tube and rod project and the housing is secured fast to the tube 10 by means of a flanged sleeve 41. Asbestos packing 42 may be provided between the tube 10 and the sleeve though other means may be employed to afford a strong fit and electrical insulation is not necessary.

The microswitch 38 may be disposed in a desired position relative to the rod end 35 by means of an adjusting screw 44 mounted on the housing 40 and rotated by an index knob 45 cooperating with a dial 46. To protect the mechanism of the switch 38 it may be desirable to provide the rod end 35 with a cap 48 with a strong spring 49 therein, so that when the portion 16 of the tube 10 cools and shortens (at say room temperature) the spring 49 absorbs motion between the rod and button 36. However the spring and cap may be omitted and satisfactory operation has been obtained by having the rod engage directly against the button even when the switch position is for high temperatures and the device has been allowed to cool to room temperature.

The coefficients of expansion to Inconel and Kanthal are of the same order and very nearly the same. No material error arises due to expansions of the rod 22 and tube 10 in the vicinity of the kiln wall 15 as they are both of about the same extent.

Thus far the description has concerned merely a thermostatically controlled or actuated switch and such a device would be operative. The adaptation of such a device to form a thermometer as well as the thermometer requires no change and very few additions.

As stated in my above mentioned application Serial Number 389,278 the Inconel-Kanthall thermocouple has almost the identical characteristics as has the platinum-rhodium couple, up to about 2400° F. The characteristics are about the same both as to the E. M. F. and the E. M. F.-temperature coefficient.

In adapting the above described instrument I have disposed a Kanthal wire 50 in the bore of the porcelain tube 18 and welded one end 51 of the wire to the rod 22 and brought the other end 52 out the hole 12 and welded it to the end 11 of the Inconel tube, the weld at 52 constituting the "hot" junction.

A piece 54 of Kanthal is welded onto the end 21 of the tube 10 in the housing 40 and this constitutes the "cold" junction. Suitable conductor leads 55 and 56 are attached as at 58 and 59 to the piece 54 and to a Kanthal part of the rod 22. E. M. F. or temperature values may be indicated by a suitable meter 60 connected to the leads 55 and 56 and which may be mounted on the housing.

In use the meter 60 and dial 46 are calibrated for desired scales. The switch 38 is employed to control an input of heat energy to the device whose temperature is to be controlled, such as a kiln or the like.

The metals A and B may be interchanged if the interchange is complete. Thus if the tube 10 is of metal A, the rod 22, wire 50 and piece 54 must be of metal B. If the tube 10 is of metal B, the rod, wire and piece must be of metal A. An interchange of metals of course requires that the leads 54 and 55 be swapped

if the same scale or meter 60 is retained. Of course if the thermocouple action is not desired rod 22 may be, and preferably is, of the same material as tube 10.

The invention claimed is:

1. In a thermocouple a junction of metals A and B, 5 A having the approximate composition

	Per cent
Ni	79.5
Cr	13.0
Fe	6.5
Mn	0.25
Si	0.25
Cu	0.20
C	0.08

and B having the composition

	Per cent
C	0.25 max.
Si	0.3-2.0
Cr	18-25
Al	3.5-6.5
Co	Nil-3.0
Ta	Nil-3.0
Mn	0.2-1.0
Fe	Balance

2. In a temperature responsive instrument, a metallic tube substantially closed at the inner end and having a porcelain tube therein coaxially therewith and abutting against said tube end, a rod-like transmission member of different metal from that of the tube and insulated therefrom and in the metallic tube and having a part against an end of the porcelain tube, the member projecting from the outer end of the metal tube, the member being for transmitting relative movement of longitudinal expansion of the tubes, a switch substantially fixed with respect to the outer end of the metal tube and having a part adapted to be engaged by the outer end of the member, the metals of the member and tube having a melting point as high as about 2400° F., coefficients of thermal expansion of the same order and greater than that of porcelain, and having different temperature-E. M. F. relationships.

3. In a temperature responsive instrument, a metallic tube substantially closed at the inner end and having a porcelain tube therein coaxially therewith and abutting against said tube end, a rod-like transmission member of different metal from that of the tube and insulated therefrom and in the metallic tube and having a part against an end of the porcelain tube, the member projecting from the outer end of the metal tube, the member being for transmitting relative movement of longitudinal expansion of the tubes, a switch substantially fixed with respect to the outer end of the metal tube and having a part adapted to be engaged by the outer end of the member, the metals of the member and tube having a melting point as high as about 2400° F., coefficients of thermal expansion of the same order and greater than that of porcelain, and having different temperature-E. M. F. relationships, and a conductor of the same metal as that of the transmission member and loosely disposed in the bore of the porcelain tube and having one end electrically secured to the member and the other end to the inner end of the metal tube.

4. In a temperature responsive instrument, a metallic tube substantially closed at the inner end and having a porcelain tube therein coaxially therewith and abutting against said tube end, a rod-like transmission member of different metal from that of the tube and insulated therefrom and in the metallic tube and having a part against an end of the porcelain tube, the member projecting from the outer end of the metal tube, the member being for transmitting relative movement of longitudinal expansion of the tubes, a switch substantially fixed with respect to the outer end of the metal tube and having a part adapted to be engaged by the outer end of the member, the metals of the member and tube having a melting point as high as about 2400° F., coefficient of thermal expansion of the same order and greater than that of porcelain, and having 75

different temperature-E. M. F. relationships, one metal A having approximately the composition

	Per cent
Ni	79.5
Cr	13.0
Fe	6.5
Mn	0.25
Si	0.25
Cu	0.20
C	0.08

and the other metal B having the composition

	Per cent
C	0.25 max.
Si	0.3-2.0
Cr	18-25
Al	3.5-6.5
Co	Nil-3.0
Ta	Nil-3.0
Mn	0.2-1.0
Fe	Balance

5. An instrument as claimed in claim 3, one metal A having the approximate composition

	Per cent
Ni	79.5
Cr	13.0
Fe	6.5
Mn	0.25
Si	0.25
Cu	0.20
C	0.08

and the other metal B having the composition

	Per cent
C	0.25 max.
Si	0.3-2.0
Cr	18-25
Al	3.5-6.5
Co	Nil-3.0
Ta	Nil-3.0
Mn	0.2-1.0
Fe	Balance

6. An instrument as claimed in claim 5, the metal tube being of metal A.

7. In an instrument as claimed in claim 3 and a piece of metal of the same as that of the wire welded onto the outer end of the metal tube, and an E. M. F. meter connected to the piece and the outer end of the member.

8. In an instrument as claimed in claim 7 one metal A having approximately the composition:

	Per cent
Ni	79.5
Cr	13.0
Fe	6.5
Mn	0.25
Si	0.25
Cu	0.20
C	0.08

and the other metal B having the composition:

	Per cent
C	0.25 max.
Si	0.3-2.0
Cr	18-25
Al	3.5-6.5
Co	Nil-3.0
Ta	Nil-3.0
Mn	0.2-1.0
Fe	Balance

9. In an instrument as claimed in claim 3, the metal tube having the double function of an expansion and thermocouple element.
